CLAIM

The ornamental design for a storage container, as shown and described.

DESCRIPTION

FIG. 1 is a front elevation view of a first embodiment of a storage container showing our new design;

FIG. 2 is a front elevation view of a second embodiment of a storage container showing our new design;

FIG. 3 is a rear elevation view of FIG. 1;

FIG. 4 is a rear elevation view of FIG. 2;

FIG. 5 is a top plan view of FIG. 1;

FIG. 6 is a top plan view of FIG. 2;

FIG. 7 is a bottom plan view of FIG. 1;

FIG. 8 is a bottom plan view of FIG. 2;

FIG. 9 is a left side elevation view of FIG. 1, the right side elevation view being a mirror image, the left side elevation view and right side elevation view of FIG. 2 are identical to FIG. 9;

FIG. 10 is a top perspective view of FIG. 1.

FIG. 11 is a top perspective view of FIG. 2; and,

FIG. 12 is an enlarged portion view taken from encircled portion labeled, "FIG. 12," in FIG. 1.

The broken lines show environmental structure and form no part of the claimed design.

The small oval shown in FIGS. 1, 2, 10, 11, and the enlarged view in FIG. 12 is in broken lines and forms no part of the claimed design.

The long dash-short dash-long dash line shown in FIGS. 5 and 10 represent shading.

1 Claim, 8 Drawing Sheets
